Attorney.

UNITED STATES PATENT OFFICE.

CHARLES DEFREESE, OF LA FAYETTE, INDIANA.

SCOOP BOARD.

Application filed December 28, 1921. Serial No. 525,836.

To all whom it may concern:

Be it known that I, CHARLES DEFREESE, a citizen of the United States, residing at La Fayette, in the county of Tippecanoe and State of Indiana, have invented certain new and useful Improvements in Scoop Boards, of which the following is a specification.

This invention relates to improvements in end gate construction for wagons, the principal object being to provide a simply constructed scoop or shoveling board which can be quickly attached or removed from the wagon body.

A further object is to provide a scoop board which can be applied to the body without additional attaching devices being applied thereto.

A still further object is to provide a scoop which can be readily operated without being hinged to the body of the wagon to which it is applied.

With these and further objects in view, my invention resides in the novel features of construction, combination and arrangement of parts which will hereinafter be more particularly described and claimed and shown in the drawings wherein:—

Figure 1 represents a side elevation of a wagon body, illustrating my improved scoop board applied thereto, said board being shown in raised position.

Fig. 2 is a similar view, illustrating the board in lowered position.

Fig. 3 is a rear view of the wagon body with the scoop board in raised position.

Fig. 4 is a central vertical longitudinal section through a portion of the wagon body and scoop board, and

Fig. 5 is a detail elevation of one of the side members.

As shown in the several figures of the accompanying drawings, my invention is applied to a wagon body 1 of ordinary construction provided with the usual bottom 2 to which the side boards 3 are applied. A transverse brace bar 4 is secured to the under side of the bottom of the body at its rear end as is usual in devices of this character, the ends of said bar projecting beyond the side boards 3 as shown at 4. Upright cleats 5 and 6 are secured to the side boards adjacent their rear ends to provide channel-ways 7 in which the ordinary end gate slides, said gate however, being removed when my improved scoop board is applied. In the channels 7 are placed the upright supports 8

preferably faced with metal strips 9 as shown, these supports being held in position by the plates 10 and 11, which are secured by the bolts 12, said bolts passing through apertures in the side boards of the wagon. It is unnecessary to provide additional apertures for the bolts 12 because in a wagon of ordinary construction these apertures are used for the end gate brace rod, which rod is removed when my improved scoop board is applied. These upright supports 8 preferably project above the side boards 3 and aid in holding supplemental side boards in position, should it be necessary to use the same, and they may be formed in several parts or as shown in the drawings.

Plate members 13 are secured to the upright supports 8, one of these members being secured to each support preferably by rivets 14 and 15. Each of the members 13 is provided with straps 16 and 17, which are formed integrally therewith. Each of these straps is bent over eye-bolts 18, disposed therein. These members 13 are each secured to the inner side of the supports 8 and project rearwardly of the side boards and cooperate with the end gate or scoop board when it is in raised position. This scoop board comprises a bottom 19 of a width substantially equal to the distance between the side boards 3 of the wagon body, its lower edge being beveled off as shown at 20 and resting on the bottom 2 of the wagon body. This lower inner edge acts as a fulcrum for the scoop board when the same is moved from its lower to its raised position or vice versa. The bottom 19 is provided on its outer or lower face with a pair of wedge members 21 which taper from their inner toward their outer ends, one of these members being secured adjacent each side edge of the bottom and preferably flush therewith, the inner end of the members terminating at points spaced inwardly from the inner edge of the bottom as shown. These wedge pieces 21 serve as spacing blocks to space the strips which form the flange members 22 away from the bottom 19, these flanges being secured to the outer side of the wedge members and extended beyond the side edges of the bottom.

To the outer edges of the flanges 22 the side members 23 are secured, thereby forming a seat on each side of the bottom 19 which receives the outer ends of the side boards 3 when the scoop board is in its

raised position as shown in Fig. 1. The inner ends of the flange members 22 terminate flush with the inner ends of the wedge members 21 at points spaced from the fulcrum edge of the bottom 19 while the inner ends of the side members 23 preferably extend until they are flush with the said edge of the bottom. These parts of the scoop board are held together by means of brace pieces 24 and 25, each of which has a thickened central portion whose longitudinal edge contacts with and is secured to the bottom 19, the ends engaging the inner edges of the wedge and flange members 21 and 22. The outer end portions of the brace pieces are relatively thin and underlie the flange members to support the same; the side members 23 also are engaged by these portions of the braces. These side members 23 are also inclined from their inner toward their outer ends as shown.

By providing the wedge members 21, the fulcrum edge of the bottom 19 is maintained in close contact with the bottom of the wagon body 1 throughout the entire extent of the movement of the scoop board. In this manner also the ends of the flanges 22 are enabled to engage the ends of the side boards of the wagon to maintain a tight fit at all times, but the principal advantage of these wedge members is to allow the scoop board to be readily moved from one position to another without hinging the same to the body of the wagon.

It will be seen that from the several figures of the drawings that when the scoop board is in its raised position, the bottom 19 will have its side edges contacting with the side boards of the body on their inner surfaces while the side members of said board will engage the outer faces of the side boards 3, the ends of said side board resting in the grooves. When in the last mentioned position, the scoop board receives the bolts 18 in the openings 26, the inner portions of which are enlarged to guide said heads thereinto. The heads of the eye bolts extend through said openings and are engaged by the hooks 27 on the ends of the retaining links 28, said links being adapted to spring under the catches 29 preferably secured to the brace pieces 24 on the outer side of the scoop board. When each of the links 28 is snapped under these catches, said scoop board will be retained in its upright closed position until they are removed therefrom. The eye bolts 18 each have their opening nearer one side than the other, the distance between the opening and the adjacent side being substantially the thickness of the head

of the bolt. This is to permit the hooked ends 27 of the links 28 to be readily disengaged from the bolts at will.

For further supporting the scoop board upon the wagon bottom 2, when in extended position, I provide the bar members 30 and 31 which have their end portions 32 and 33 disposed at an angle in opposite directions from the vertical portions 34. The vertical portions 34 of the bar members 30 and 31 extend through openings in the strap plates 35 and 36 connected to the flanges 22. The end portions 32 engage the lower surface of the side members 23, while the end portions 33 engage under the bottom 2 of the wagon. The coil springs 37 and 38 are secured at 39, to the lower end of the side members 23 and their free ends are formed with hooks 40, which engage the end portions 32 of the bar members 30 and 31 and serve to tension the same into locking position.

From the foregoing description of the construction of the device, the operation thereof will be readily understood without further discussion, and from this description it will be seen that I have invented an extremely simple scoop board which can be applied to a wagon body which will operate without being hinged thereto as is necessary in most cases of this character.

I claim as my invention:—

The combination with a wagon body, including a transverse brace bar, at its rear end extending beyond the sides thereof, of a scoop board, cleats secured to the wagon sides, upright supports adjustably mounted between said cleats, plates attached to said cleats for holding said upright supports in position, plate members attached to said supports, bolts mounted in said plate members, links connected to said bolts and extending through said scoop board, catches arranged on said board and adapted for engagement with said links for retaining said scoop board in closed position, bar members connected to said scoop board and with their end portions disposed at an angle in opposite directions with their vertical portions extended through openings in strap plates secured to the side members adapted for detachable connection with the wagon body for retaining said scoop board in open position, and springs for tensioning said bar members in position.

In testimony whereof I affix my signature in the presence of two witnesses.

CHARLES DEFREESE.
